READER FOR PUNCHED CARDS AND MARK-SENSE DOCUMENTS

Donald Van Der Linden, Phoenix, Ariz., assignor to Motorola, Inc., Franklin Park, Ill., a corporation of Illinois

Filed Nov. 13, 1967, Ser. No. 9,389

Term of patent 14 years

(Cl. D26—5)

FIG 1

FIG. 3

FIG. 5

FIG. 1 is a perspective view of a reader for punched cards and mark-sense documents embodying my new design;

FIG. 2 is a top plan view thereof;

FIG. 3 is a front elevation thereof;

FIG. 4 is a side elevation thereof; and

FIG. 5 is a rear elevation thereof.

The dominant features of my design reside in the portion shown in full line.

I claim:

The ornamental design for a reader for punched cards and mark-sense documents, as shown and described.
